UNITED STATES PATENT OFFICE

RAYMOND E. GUYTON, OF LOS ANGELES, CALIFORNIA, ASSIGNOR OF ONE-HALF TO THEO R. BARKS, OF LOS ANGELES, CALIFORNIA

LOCK

Application filed May 14, 1930. Serial No. 452,306.

My invention pertains to a type of lock having what may be termed a stationary barrel and a rotatable sleeve mounted on the barrel, the sleeve being connected to the knobs 5 of the door and being operable to actuate the locking bolt for the door.

In this type of lock an object of my invention is a construction for locking or unlocking the rotatable sleeve in relation to the barrel whereby when the sleeve is locked to the barrel it is prevented from movement and when unlocked it may be rotated, and, in which, when the sleeve is unlocked by a suitable key construction used on the outside of 15 the door, that the lock may be re-set on the inside without the use of a key and thus again securely lock the door on closing thereof.

Another object and feature of my invention is the construction of a lock wherein the barrel is provided with a plurality of longitudinal slots, each carrying a sliding strip with a locking and a false detent mounted on each strip. The locking detent engage a 20 head on the sleeve and prevent rotation of the sleeve until by a special key operable through the knob on the outside of the door the proper sliding strips are shifted longitudinally to release the locking detents from the head of the sleeve.

Another object and feature of my invention is constructing the sliding strips with the false detents and the head construction of the sleeve whereby if these false detents are shifted in the endeavor to pick the lock 25 that they will be brought into locking position with the head and prevent rotation of the sleeve on the barrel. Another detailed object and feature of my invention is constructing the locking and false detents and 30 the sliding strips on which they are mounted with a lost motion whereby a person endeavoring to pick the lock cannot detect any slippage or change of pressure when exerting a slight turning pressure on the knob on the 35 outside of the door and then endeavoring to pick the lock by shifting the sliding strips.

Another feature of my invention is that the sliding strips with the false and locking detents may be interchanged to readily 40 change the combination, and this combined

with a key structure having a series of projecting pins which may be changed in the key in accordance with the changes in the combination of the lock. In this connection another feature of my invention is a lock normally operated by a key which, when the combination is known, may be actuated as a combination lock by shifting the proper sliding strips with their detents. Another detailed feature of my invention comprises a 45 re-setting device for the sliding strips and the detents mounted on the axial center of the inner door knob which, when the door is closed, may be used to shift the strips so as to bring the locking detents into engagement with the head on the rotatable sleeve. 55

My invention is illustrated in connection with the accompanying drawings in which:

Fig. 1 may be considered as a vertical section through a door illustrating the knobs in section and the interior construction in elevation, with the lock bolt in section.

Fig. 2 is a view similar to Fig. 1 except being a longitudinal section through the interior parts of the lock when in the locked 75 position.

Fig. 3 is a view similar to Fig. 2 with the parts in the unlocking position.

Fig. 4 is a transverse section on the line 4—4 of Fig. 2 in the direction of the arrows. 80

Fig. 5 is a transverse section on the line 5—5 of Fig. 2 in the direction of the arrows.

Fig. 6 is a transverse section on the line 6—6 of Fig. 2 in the direction of the arrows.

Fig. 7 is an end elevation taken in the direction of the arrow 7 of Fig. 2.

Fig. 8 is an end elevation taken in the direction of the arrow 8 of Fig. 2.

Fig. 9 is a perspective view of the stationary barrel.

Fig. 10 is a perspective view of part of the stationary barrel with the rotatable sleeve thereon with parts broken away.

Figs. 11 and 12 are elevations of the sliding strips with the locking and false detents mounted thereon.

Figs. 13 and 14 are detailed sections through the head of the sleeve and barrel showing the locking detents in the locking and unlocking position.

Figs. 15 and 16 are details similar to Figs. 13 and 14 of the false detents in their free and locking position.

Fig. 17 is a detailed perspective view of the pin fitting in the bore of the barrel.

Fig. 18 is a detailed perspective view of the key.

Fig. 19 is a transverse section on the line 19—19 of Fig. 3 in the direction of the arrows.

10 Referring first to Figs. 9 and 10 in which is illustrated the stationary barrel 11 which is preferably cylindrical and has a flange 12 at one end with a reduced section 13 at the other end. There is a central bore 14 extending axially through the barrel. The barrel has shoulders 15 at the end next the reduced section 13, and extending from the extreme end 16 there are a pair of diametrically opposite slots 17 in this reduced section. 15 Extending lengthwise of the center section 18 of the barrel and through the flange 12 there are a plurality of slots 19, these slots extending substantially as deep as the shoulders 17. All the slots are arranged the same and 20 there may be any number of slots in accordance with the number of locking and false detents it is intended to use in the lock. In 25 the illustration presented slots 19 are arranged in diametrically opposite pairs although it is manifest that this arrangement 30 is not necessary.

Rotatably mounted on the barrel there is a cylindrical sleeve designated generally by the numeral 20. This sleeve has an end 21 which abuts against the flange 12 of the barrel and has a head 22 with an annular groove 23 back of the head, thereby forming a rim 24 on the extreme end of the sleeve. This rim is provided with rim slots 25 extending 35 through the periphery of the rim 24 to the bottom of the groove 23, and on the face of the head there are a series of radial grooves 26. These are adapted to register with the slots 19 in the barrel.

40 45 Fitted in the slots 19 of the barrel there are flat sliding strips 27 (note Figs. 11 and 12). These strips have a narrow section 28 with a shoulder 29 and with a projecting head 30 at the end. Fitting in this reduced section 28 of certain of the strips there are locking detents 31. These are illustrated as having a stem 32 fitting on the reduced part 28 of the sliding strips and having a block-like structure 33 at the end. This block-like structure has a cutout corner indicated at 34 to fit over the bead 30 on the locking strip. There is a clearance space 35 to allow for lost motion between the end of the detent and the shoulder 29.

an opening 39 with a projecting finger 40. There is a clearance space 41 between the end of the stem of this false detent and the shoulder on the locking strip. I usually make the clearance indicated at 35 about twice the 70 clearance indicated at 41, but the sliding strips with their detents only have a limited motion as pointed out hereinunder.

The sleeve 20 when assembled in the door is provided with a collar 42 which is secured 75 to the sleeve by a screw 43, and on one side of the collar there is a projecting stud 44, this being secured by a screw 45 (note particularly Figs. 1, 2, 3, and 4). This stud has a curved cam surface 46 and is adapted to fit 80 in a slot 47 in a latch bolt 48, which bolt is slideable in a bore 49 in the door. There is a pin 50 which extends through the bolt 48 and is engaged by the compression spring 53, which spring bears against the pin and the 85 end 54 of the bore 49. The door is provided with the usual face plate 52. The bolt has a beveled latch end 55. It will thus be seen that when the sleeve 20 on the barrel is rotated it can withdraw the latch bolt, and that this is then urged to its outward position, reversing the rotation of the sleeve 20.

The pin 62 is provided with a cage for 105 locking and unlocking the lock from the inside. This cage is designated generally by the numeral 65 (note particularly Fig. 18) and such cage has a cylindrical section 66 with an end plate 67, this end plate having an 110 opening 68 to fit over the reduced end 13 of the barrel 11, and on the inside of the face plate there is a collar 69 sliding on the reduced section 13. This collar has a plate 70 extending diametrically therethrough, which plate fits in the groove 17 of this reduced section 13. The plate and the collar 69 are secured to the pin 62 by a pin or screw 71. The opposite end of the cage has a ring 72 attached to the cylindrical section 66 and 115 adapted to have a sliding fit on the outside of the sleeve 20. As this cage is secured to the pin 62 it slides with the pin. The inside face

rel and has tongues 75 fitting in the groove 17 (note particularly Figs. 2, 3, and 5). There are curved slide strips 76 which have prongs 77 secured to the escutcheon plate 78 on the inside of the door. A nut 79 threaded on the end of the reduced section of the barrel retains the barrel attached to this bridging piece. This construction, therefore, prevents longitudinal and rotational movement 10 of the barrel.

The rotatable sleeve 20 is connected to the inner knob 80, which knob has a skirt 81 which is attached to arcuate plate extensions 82 of the collar 42. These extensions operate in arcuate slots 83 in the escutcheon plate 78 on the inside of the door and, as the collar 42 is connected to the rotatable sleeve 20, the rotation of the inner knob 80 rotates the rotatable collar 42.

20 This knob also functions in limiting the movement of the pin 62 and, hence, of the sliding strips 27 and the detents carried thereby. The construction for this purpose utilizes a narrow internal flange 84 at the opening 85 in 25 the center of the inner knob, there being a recess section 86 to give a space for the fingers to engage a pivoted dog 87, which dog has a pivotal connection 88 to the pin 62 at the inside end. The dog is circular in cross section 30 and has an inner groove 89 with right angular shoulders and an outer groove 90 with a right angular shoulder on the inside and a bevel 91 on the outside. The outer portion 92 of this dog is cylindrical and has a 35 knurled surface to afford a ready finger grip.

The key designated generally by the numeral 93 is illustrated particularly in Figs. 18 and 3, and such key comprises a disk 94 secured to a tubular stem 95. This stem has 40 a head 96 on its outer end and secured to the disk there are a plurality of pins 97 inserted in sockets 98 in the disk. These pins may be changed in location in order to change the combination of the lock. The key can only be 45 inserted in one manner in the lock as the passage 99 through the center of the stem 95 is shaped to conform to the end 61 of the pin 62, that is, it is partly cylindrical and has a flat surface to fit on the partly cylindrical and 50 partly flat surface of the outer end of the pin.

A cup 100 is slidably mounted on the stem 95 and surrounds the disk and also forms an enclosure for the pins 97. This cup is pressed toward the disk by a compression spring 101 coiled on the stem 95 and the head 96 and the cup. As the pins are inserted through the 55 perforations 59 in the web 58 of the outer knob the cup recedes from the position shown in Fig. 18 to that shown in Fig. 3.

60 The manner of operation and functioning of my lock is substantially as follows:

Presuming the lock is in the locked position, the sliding strips 27 with the locking and false detents mounted thereon, as well as the pin 62, are drawn to a position to their furthermost

position toward the outermost knob such as is shown in Figs. 1 and 2. When the pin 62 is drawn outwardly the dog 87, which may oscillate slightly on its horizontal pivot in a vertical plane, is in a downward position so 70 that the narrow internal flange 84 of the inner knob forms a support for the beveled surface 91 of the dog.

In this locking position the locking detents 31 on the sliding strips have their block-like 75 end 33 engaged in the rim slots 25 and the radial slots 26 in the rim 24 of the head 22 on the inner end of the rotatable sleeve 20. These, therefore, lock this sleeve to the stationary barrel so that the sleeve cannot be 80 rotated and, hence, any rotational pressure on either the outer or the inner knob would fail to rotate the sleeve 20 and, hence, the latch bolt cannot be moved. Also, when the lock is 85 in this locked position the false detents 36 have the hook fitting over the rim 24, that is, this rim rides in the opening 39 and the projecting finger 40 fits in the annular groove 23 in the head 22 of the rotatable sleeve. It is 90 to be understood that, as above mentioned, there may be any desired number of the locking detents in proportion to the false detents, and that these may be readily changed by fitting these various detents to the different 95 sliding strips 27 and, of course, changing the combination in the key to correspond.

When it is desired to unlock the lock from the outside using the key, the pins on the key are inserted through the perforations in the web of the outer knob and, as above mentioned, the key can only be inserted in one position on account of the passage 99 having to register with the outer end of the sliding pin 62. The pins on the key engage the sliding strips 27 having the locking detents and the first motion is to take up the lost motion space 35 before these detents start to move. At the same time, the inner end 30 of the sliding strips 27 having the detents engages the 100 face 73 of the collar 69 of the cage 65 which is secured to the pin 62 and causes this to slide slightly inwardly until the annular right angular shoulder of the outer groove 90 of the dog 87 is brought forcibly against the inside edge of the narrow internal flange 84 of the inner knob. This forms a limit to the inward movement of the pin 62 and also to the inward movement of the sliding strips 27 and the detents carried thereby. This movement 105 effected by the pins on the key is sufficient to move the blocks 33 of the locking detents 31 out of engagement with the rim slots 25 and the radial slots 26 on the head 24 of the rotatable sleeve, so that then this sleeve may 110 be rotated by rotating the outer knob and, hence, the latching bolt may be withdrawn 115 to unlock the door.

Presuming the door is locked and it is desired to unlock this from the inside in order to allow opening the door either by the out- 120 125 130

side or by the inside knob a person on the inside may grasp the knurled end 92 of the dog 87 and pull this outwardly of the lock, such action slides the pin 62, moving the cage 65 which, through the medium of the ring 72 attached to the cylindrical section 66, engages the inner portion of the blocks 33 of the locking detents 31 and of the blocks 37 of the false detents 36 and draws these outwardly. A person may draw this pin 62 outwardly of the lock until the right angular shoulder of the outer groove 90 engages the narrow internal flange 84 or until the inner groove 89 engages this flange. In the first case the locking detents are disengaged from the rim 24 of the rotatable sleeve 20 and in the latter case all of the detents are removed sufficiently to be free of the rim 24 and, hence, the sleeve 20 may be rotated by either the outer or the inner knobs and the bolt withdrawn for opening the door. To lock the door from the inside it is only necessary to press inwardly on the dog 87 thus returning the pin 62 and the sliding strips 27 with their detents to the locking position. These latter are thrust inwardly by engaging the surface 73 of the collar 69 attached to the pin 62.

An object of forming the locking and the false detents separate from the sliding strips 27 and having a lost motion space 35 and 41 (note Figs. 11 and 12) is to make it extremely difficult to pick this lock for a person who does not know the combination. If these strips 27 and the detents were made in one solid piece both in the locking and the false form and the person on the outside brought a rotational pressure to bear on the outer knob and at the same time with a pin-like instrument thrust inwardly on the ends of the sliding strips, a skilled lock picker could readily detect by the pressure against and the ease with which these strips would slide which were the locking detents and which were the false detents, but where there is the lost motion the pressure on any of the sliding strips 27 causes a free sliding of all of these until the lost motion space is taken up and, moreover, on account of the false and locking detents being separate from the sliding strips 25 the lateral pressure on these is not so noticeable as if they were formed integral with the sliding strips. It will thus be seen that it is difficult for an experienced lock picker to determine which sliding strips carry the locking and which the false detents, presuming, of course, that such lock picker understands the full mechanism of the lock. Presuming a person is endeavoring to pick the lock, the function of the projecting finger 40 on the false detents 36 is that if the sliding strip carrying such detent is pressed inwardly by a pin-like implement this finger is brought into the rim notch 25 of the rim 24 of the head of the rotatable sleeve and, hence, in the endeavor to

pick the lock the party so operating brings another detent into the locking position so that even should he thrust some of the locking detents out of locking position and some of the false detents into the locking position, the lock can still not be opened, and it is manifest that with a large number of slots in the stationary barrel the combinations which would have to be worked out are so enormous in number that it is hopeless to try all the possible combinations in an endeavor to pick the lock, and, moreover, when a person endeavoring to pick the lock thrusts the sliding strips 27 inwardly with the detents carried thereby he has no way of withdrawing these outwardly again.

Various changes may be made in the details of construction without departing from the spirit or scope of the invention as defined by the appended claims.

I claim:

1. A lock having a stationary barrel and a rotatable sleeve thereon and a bolt operated by the sleeve, interlocking means slidable longitudinally of the barrel and the sleeve to lock or unlock the sleeve relative to the barrel to prevent or permit rotation of the sleeve.

2. A lock having a stationary barrel, a sleeve rotatable thereon, a bolt operated by the sleeve, slidable locking means in the barrel to interlock with the sleeve to prevent or permit rotation of the sleeve, said locking means being operable by a key engaging said locking means at the outer end of the barrel.

3. A lock as claimed in claim 2, a manually operable device with an operative connection to the locking and unlocking means on the sleeve at the end opposite the key applying end to unlock or lock the sleeve to permit or to prevent rotation thereof.

4. A lock having a stationary barrel, a rotatable sleeve thereon with an outer knob, locking and unlocking devices slidably mounted in the barrel and interconnecting with a sleeve to lock or unlock said sleeve to prevent or permit rotation thereof, said devices being engageable by a key insertable through the knob into the barrel.

5. A lock as claimed in claim 4, an inner knob having a connection to the sleeve, a releasing device slidable through the knob and having an inter-connection with the locking devices to slide said devices to unlock or lock the sleeve to the barrel.

6. A lock having a stationary barrel with a series of longitudinal slots, a sleeve rotatable on the barrel, sliding strips having locking detents in some of the slots, said detents in one position locking the sleeve to the barrel, said sleeve being adapted to actuate a bolt on rotation, said sliding strips being adapted to be actuated to unlock the sleeve by engaging said strips at the outer end of the barrel.

7. A lock as claimed in claim 6, other of the slots in the barrel having sliding strips with false detents therein, said false detents having means to interlock with the sleeve when shifted longitudinally by a wrong key or on an endeavor to pick the lock.

8. A lock having a barrel with a plurality of longitudinal slots, means to secure said barrel in a stationary position with reference to a door, a sleeve rotatable on the barrel and having a head, said sleeve being adapted to actuate a bolt, a plurality of sliding strips mounted in the slots, some having a locking detent and others a false detent thereon, the locking detents engaging the said head to lock the sleeve to the barrel, and being operable by a proper key to unlock the sleeve from the barrel, and the said false detents being adapted on shifting longitudinally inwardly to engage the said head to lock the barrel in the sleeve.

9. A lock as claimed in claim 8 having a knob on the inside connected to the sleeve to rotate same and a pivoted dog to engage part of the said knob, said dog being slideable in relation to the barrel and having a connection to slide the said detents and the sliding strips to unlock or to lock the sleeve to the barrel.

10. A lock having a barrel with a plurality of longitudinal slots, central means to secure said barrel in a stationary position in reference to a door, a sleeve rotatable on the barrel and having outer and inner knobs connected to the sleeve to rotate same, the sleeve being adapted to operate a bolt, a plurality of sliding strips in the slots, some having locking and others having false detents, the sleeve having a head thereon with grooves, said grooves being engaged by the locking detents when in the locking position, the strips and the locking detents being adapted for longitudinal movement toward the inner knob when actuated by a proper key inserted through the outer knob, the said strips having the false detents remaining stationary when a proper key is applied but being shifted inwardly on the application of an incorrect key or on an attempt to pick the lock by thrusting said latter strips inwardly, the false detents having means to engage the slots in the said head and thereby lock the sleeve to the barrel.

11. A lock as claimed in claim 10, the barrel having a longitudinal bore with a pin slideable therein, a cage structure connected to the pin and being shiftable inwardly on the inward shifting of the sliding strips having the locking detents, the inner knob having a central opening, a dog pivotally mounted on the inner end of the pin adapted to interengage with the inner knob at the said opening, and the dog interconnecting with the knob forming a limit to the movement of the detents.

12. A lock having a barrel with a plurality

of longitudinal slots, means adapted to interconnect the barrel and door upon which the barrel is mounted to retain the barrel stationary, a sleeve rotatable on the barrel and having a head, said sleeve being adapted to 70 actuate a bolt, an outer and an inner knob operatively connected to the sleeve, the said slots each having a slideable strip, some with a locking detent and others with a false detent, the locking detents inter-connecting with the said head when in the locking position to lock the sleeve to the barrel, the inner knob having a central opening, the barrel having a central bore with a pin 80 extending longitudinally therethrough, a dog pivotally connected to the pin and passing through the opening in the inner knob, a cage on the pin having means to inter-connect with the detents to slide said detents into 85 unlocking position, a long, reverse movement to return the detents to a locking position, the false detents being slideable in the barrel to interengage with the said head to lock the sleeve to the barrel.

In testimony whereof I have signed my name to this specification.

RAYMOND E. GUYTON.
